The ornamental design for a display screen with graphical user interface, as shown and described.

DESCRIPTION

FIG. 1 is a front view of the first image of a display screen with graphical user interface showing our new design; and, FIG. 2 is a front view of the second image thereof.

The broken line drawings of the display screen and the finger are for the purpose of illustrating environmental structure and form no part of the claimed design. The broken line showing the remainder of the image in all views illustrates unclaimed portions of the design and forms no part thereof.

The appearance of the transitional image sequentially transitions between the images shown in FIGS. 1-2. The process or period in which one image transitions to another image forms no part of the claimed design.
